VACUUM CLEANER CONVERTER
ARRANGEMENTPaul T. Hahn, Detroit, Mich., assignor to Eureka
Williams Corporation, a corporation of Michigan

Application August 20, 1943, Serial No. 499,424

19 Claims. (Cl. 15—332)

1

This invention relates to vacuum cleaners and has particular reference to a novel and efficient manner of and means for converting a floor type suction cleaner into one adapted for so-called "off the floor" cleaning.

My invention has particular application to that type of floor cleaner sometimes designated as a vertical motor cleaner, although its application is not limited thereto. Such type of floor cleaner may comprise a vertical driving motor, a fan driven thereby, a floor nozzle having a communication with said fan, a surface cleaning member such as an agitator operatively associated with said floor nozzle, and a driving connection arranged in said communication and extending between the shaft of said motor and said surface cleaning member for actuating the latter.

As illustrated in the embodiments of the invention selected for purposes of illustration, the device embodying the invention comprises a converter readily separable from the suction cleaner but adapted to be connected thereto and including a hollow air conducting coupling member insertable into a port in said communication and having means for shutting off the flow of air from the floor nozzle to the fan, said coupling member also having means for breaking the driving connection between the motor and the surface cleaning member. At the end which projects from the cleaner the coupling member may have connected thereto one end of a flexible hose, to the other end of which various types of suction cleaning tools may be connected.

In its broadest aspect my invention contemplates the provision of a self-contained converter coupling for a vertical motor type of suction cleaner, and which converter coupling includes a means for shutting off the communication between the floor nozzle and the fan of the cleaner, as well as a means for breaking the driving connection between the surface cleaning member and the driving motor of the cleaner.

Principal objects of the invention are:

To provide a new and efficient form of converter for vertical motor type of suction cleaners;

To provide a suction cleaner and converter construction therefor in which the converter port is provided at the rear of the machine so that the same may be pulled around on the floor when the converter is connected thereto;

To provide a self-contained converter for suction cleaners of the vertical motor type in which the converter is self-contained and includes provisions for shutting off the communi-

2

cation between the floor nozzle and the fan, as well as for breaking the driving connection between the cleaner motor and the surface cleaning member.

5 Other objects and advantages of the invention will be apparent from a consideration of the following specification taken in conjunction with the accompanying drawings, of which there are four sheets and wherein:

Fig. 1 is an elevational view, with certain parts shown in section and others broken away, of a suction cleaner of the vertical motor type with a converter associated therewith;

Fig. 2 is a fragmentary sectional view taken 10 in a plane along the line 2—2 of Fig. 1, looking in the direction of the arrows. In this view the converter coupling is only partly inserted in the cleaner port;

Fig. 3 is a fragmentary horizontal sectional 15 view taken along the staggered line 3—3 of Fig. 1, and illustrating certain parts of the converter coupling in two different positions relative to parts of the cleaner;

Fig. 4 is a fragmentary view similar to a part 20 of Fig. 3 and illustrating in full lines certain parts of the converter when the same has been completely inserted into the cleaner converter port;

Fig. 5 is a vertical sectional view taken generally in a plane along the line 5—5 of Fig. 1, with the parts of the converter arranged as illustrated in Fig. 2;

Fig. 6 is a view similar to Fig. 5 and illustrating the converter coupling fully inserted into the converter port;

Fig. 7 is a side elevational view of the converter coupling separated from the cleaner;

Fig. 8 is a fragmentary vertical sectional view illustrating a modified form of the invention;

Fig. 9 is a plan view of the converter arranged 40 in the converter port of the cleaner, with the parts arranged as illustrated in Fig. 8; and

Fig. 10 is a view similar to Fig. 8 but with the parts arranged in a position in which the driving connection between the cleaner motor and the surface cleaning member has been broken.

As illustrated in Fig. 1, a floor type cleaner of the vertical motor type with which my invention is particularly useful includes a vertical motor 20 forming a driving means for a suction creating means which includes a fan 22 arranged in a fan chamber 24, the fan 22 being secured to the extended shaft of the motor for rotation therewith. The fan chamber is provided with 55 an inlet 26 formed by a fan eye and an outlet 28

to which a dust collecting receptacle (not shown) is adapted to be connected. The cleaner further includes a rotary surface cleaning member or agitator 30 which is rotatably mounted within the mouth 32 of the floor nozzle 34, the mouth being normally positioned slightly above the surface upon which the cleaner is supported for movement by front and rear wheels 36 and 38. An air flow communication 40 connects the nozzle 34 with the fan chamber 24 through the inlet 26 so that upon operation of the fan, dirt laden air is drawn through the mouth of the nozzle and conducted to the dirt collecting receptacle which is connected to the discharge 28 of the fan chamber.

The cleaner is provided with a pivoted handle 42 by means of which the cleaner may be maneuvered over the surface or surface covering which is to be cleaned by the machine. When the cleaner is operated on a surface covering, such as a rug, the suction at the mouth of the nozzle induced by operation of the fan 22 draws such surface covering up against the mouth 32 of the nozzle where it is acted upon by the brushes of the rotary surface cleaning member 30.

The fan 22, as previously indicated, is secured to the vertical shaft of the motor for rotation therewith and may consist of a series of blades extending in a general radial direction from the hub 44, such hub forming a continuation of the shaft of the motor and extending through the fan eye 26 substantially at the center thereof and in spaced relation with the edges defining such fan eye. The fan eye 26 as illustrated comprises a central circular opening on the under side of the fan chamber 24 having its center substantially coinciding with the center of the hub 44.

The hub 44 projects downwardly into the communication 40 at one end thereof and is provided with a pulley 46 having an endless elastic belt 48 associated therewith so as to be driven thereby. The belt 48 has driving engagement with a pulley 50 suitable formed on the agitator 30 so that normally during operation of the motor 20 the fan 22 and the agitator 30 will be driven. The belt 48 is arranged in and extends through the communication 40 between the nozzle 34 and the fan inlet opening 26, the communication 40 at its forward end opening into the back of the nozzle 34.

The communication 40, except for the removable section 52 thereof, may be formed integrally with the body of the cleaner which may consist of a casting suitably formed to provide the fan chamber 24, the communication 40, and the nozzle 34. The vertical side wall 54 of the communication 40 is provided with a converter port 56 which is adapted to be closed by a valve 58 (Fig. 5). Valve 58 may consist of a plate, conforming to the shape of the port 56, pivoted to the removable section 52 along the bottom of the port 56 and preferably has a spring associated therewith so as to bias such valve 58 to its position to close the port 56, which it will do when the converter coupling is separated therefrom. As illustrated in Figs. 3, 5 and 6, the valve 58, when the converter port 56 is open, is adapted to lie alongside the bottom wall 60 of the passageway 40 and in a recess provided therein so as to be out of the path of the converter coupling indicated generally at 62.

The converter coupling 62 is illustrated in elevation in Fig. 7 and comprises a hollow air conducting member to the end 64 of which a flexible air conducting hose is adapted to be connected.

To the other end of the hose different types of suction cleaning tools are adapted to be connected, the hose and converter coupling functioning to connect such suction cleaning tools to the intake side of the fan 22 of the cleaner. The other end of the converter has assembled thereto a belt lifter 66 and a valve 68. The converter port 56 of the cleaner is positioned laterally of the pulley 46, and the inserted end 70 of the converter may be rectangular in cross section (conforming to the shape of the port 56) and have its various walls cut away and formed as follows:

The bottom wall 72, except for the bead 74 along one edge thereof, is positioned slightly above the bottom wall 60 of the passage 40, and is cut away as indicated so as to clear an upstanding pin 76 (Fig. 2) carried by the bottom wall 66 of the passageway 40. The pin 76 is positioned just forwardly of the pulley 46 and extends upwardly into the passage or communication 40 only a slight distance.

The side wall 78 of the converter, which is positioned on the upstream side of the communication 40 relative to the hub 44, is notched or cut away as indicated at 80 so as to accommodate the strands of the belt 48 as indicated in Figs. 5 and 6 when the converter is inserted into the cleaner.

The top wall 82 of the converter at the inserted end is cut away for a substantial distance in order not to obstruct the fan opening 26, thereby to provide communication between the inside of the converter coupling 62 and the fan chamber 24 through the inlet 26 thereof.

The left hand wall 84 is cut back almost the entire width of the passage 40 so as to provide substantially an unrestricted communication between the intake of the fan chamber and the interior of the converter coupling.

The bottom wall 72 has the belt lifter 66 pivoted thereto at 86. The belt lifter 66 includes a generally flat piece 88 disposed below the wall 72 and the upstanding portion thereof which forms the part for engagement with the strand of the belt for lifting the same out of driving relationship with the pulley 46. The part 88 is bifurcated to provide a slot 90 for cooperation with the pin 76 in order to shift the belt lifter 66 from one position thereof to the other, as hereinafter described.

When the inserted end of the converter coupling 62 is inserted through the port 56, such act will swing the port valve 58 to its open position and the belt lifter 66, including part 88 thereof, will be arranged generally as illustrated in Fig. 3. At this time the slot 90 is positioned so as to receive the pin 76. A spring 92 is associated with the pivot 86 between the belt lifter 66 and the bottom wall 72 of the converter coupling 62 which biases the belt lifter to the position illustrated in Fig. 3 relative to the air conducting part of the converter coupling.

As the converter coupling 62 is moved from the position in which it is shown in full lines in Fig. 3 to its fully inserted position (that is, the one indicated by the dotted lines in Fig. 3 and by the full lines in Fig. 4), the pin 76 cooperating with the slot 90 will cause the belt lifter 66 to swing in a counterclockwise direction about its pivot and to the other position thereof. In the position in which the belt lifter is shown in full lines in Fig. 3, that part thereof which engages the strands of the belt has passed beneath the strand of the belt closest to the converter port 56 and has been brought up alongside the other

strand of the belt. As the converter coupling 62 is moved from the position illustrated in full lines in Fig. 3 to that illustrated in Fig. 4, cooperation of the pin 76 with the slot 90 will cause the belt lifter 66 to swing in an arc about the pulley 46 and to lift the belt 48 out of driving relationship therewith.

Withdrawal of the converter coupling 62 from the port 56 of the cleaner will first restore the belt lifter 66 to the position illustrated in full lines in Fig. 3, thereby reestablishing the driving connection between the belt 48 and the pulley 46.

In Figs. 2 and 5 the position of the valve 68 is illustrated when the converter coupling 62 is positioned as illustrated in full lines in Fig. 3. That is, when the converter is initially inserted in the converter port, the valve 68 is horizontally arranged above the slot 80 and is adapted to pass between the strands of the belt 48 and the fan eye 26. The slot 80, as clearly illustrated, is adapted to accommodate the strands of the belt 48. The valve 68 is fixed to a rod 94 which is slidably and pivotally supported by bearings 96 and 98. In fact, the rod 94, its connection to the valve 68 and bearings 96 and 98 form a hinge which pivotally supports the valve 68 as well as permits relative sliding movement between the valve 68 and the rest of the converter.

A spring 100 coiled around rod 94 is confined by the bearing 98 and the valve 68 for biasing the same to the position illustrated in Fig. 7. The bearing 98 is provided with a spiral groove 102 into which a lateral end 104 of the rod 94 extends so that as the valve 94 is moved relative to the rest of the converter coupling 62, it will swing between its closed and open positions. That is, the valve 68 projects beyond the converter 62 when the same is inserted in the converter port 56 and is adapted to engage the wall of the passage 40 opposite the converter port 56 before the converter 62 is properly seated in the port. After such engagement, the further insertion of the converter 62 into the port 56 will cause the valve 68 and the rod 94 on which it is mounted to remain stationary while the rest of the converter moves into its seated position. During this relative movement between the valve 68 and the converter 62, the spiral groove 102 will act on the end 104 of the rod 94 and move the valve 68 to a closed position, that is, to a position in which it closes that part of the slot 80 not occupied by the strands of the belt.

The valve 68 is suitably shaped so as to straddle one of the strands of the belt to cooperate with the wall 78 so as to effectively seal the passage 40 against the flow of air from the nozzle 34 to the fan inlet 26. That is, when the converter is positioned in the converter port 56, as illustrated in Fig. 6, the converter has broken the communication between the floor nozzle 34 and the fan, and at the same time the driving connection between the motor 20 and the surface cleaning member 30 has been broken.

As the belt lifter 66 swings through more than 90° in order to disengage the belt 48 from the drive pulley 46, the tension of the belt 48 on the belt lifter 66 will function to hold the converter 62 in the position illustrated in Fig. 4. When the converter 62 is separated from the port 56 the valve 58 will automatically close the same.

The converter port 56 faces one side of the cleaner and access thereto is provided so that the converter 62 may be inserted in the port 56 while the cleaner is supported on the wheels thereof. In this way the cleaner may be converted for "off

the floor" cleaning without turning the same on its side.

In the modification disclosed in Figs. 8, 9 and 10, a converter coupling of the same type is provided although the construction thereof is specifically different, and in addition the converter port of the cleaner faces the rear of the cleaner instead of the side thereof as in the previous modification. As the construction of the cleaner is otherwise generally the same as that illustrated in the preceding embodiment, the same reference characters have been used to indicate the same parts.

In this modification the converter port 110 faces the rear of the cleaner and is arranged below the discharge 28. The port 110 may be defined by the lower wall 112 of the fan chamber 24, a horizontal extension 114 of the bottom wall 60 of the passageway 40, and extensions 116 and 118 of the side walls 54 and 117 of the communication 40. This port may be rectangular in cross section and is normally closed by a valve 120 similar to the valve 58 and which is adapted when open to lie in a recess formed in the bottom wall 114. A spring (not shown) is adapted to bias the valve 120 to a position to close the converter port.

The converter indicated generally at 122 comprises a hollow air conducting member having a cross section adapted to fit that of the port 110 and includes top wall 124, side walls 126, and bottom wall 128. The top wall 124 is cut out so that the edge at the inserted end thereof conforms to the shape of the fan eye 26 when the converter 122 is in its inserted position, while the side walls 126, at a position substantially opposite the pulley 46 when the converter is in its inserted position, are curved toward each other so as to provide curved wall portions 130 which extend across the passage 40. The curved wall portions are interrupted to provide a slot 132 which is adapted to straddle the pulley 46 and the belt 48 when the converter 122 is inserted in and removed from the cleaner. The bottom wall 128 ends at the wall portions 130 and merges therewith.

A rotary cup-shaped member 132' is pivoted by pin 134 to the bottom wall 128 of the converter. The cup-shaped member on its upper side is provided with a U-shaped bracket 134' which carries a shaft 136 which forms a pivotal support for a belt lifter 138, spring 140 being coiled around shaft 136 and acting on belt lifter 138 so as to bias the same to the position illustrated in Figs. 8 and 9.

The belt lifter 138 includes an upstanding finger 139 which is adapted to engage the lowermost strand of the belt 48, as is clearly indicated in Fig. 8, when the cup-shaped member 132' is rotated in a counterclockwise direction about its pivot 134.

Cable 142 is coiled around the vertical cylindrical wall of the cup-shaped member 132' and extends backwardly and passes over rollers 144 and is coiled around a sleeve 146 which is rotatable on a cylindrical extension 148 of the converter 122. The cable 142 is anchored to the sleeve 146 so that when the sleeve 146 is turned, the cup-shaped member 132' will be correspondingly turned about its pivot. For example, with the parts arranged as illustrated in Fig. 9 when the sleeve 146 is turned in the direction of the arrow, the cup-shaped member will be turned in a counterclockwise direction about its pivot. This will shift the belt lifter 138 so that the finger 139 thereof will engage the lowermost strand of the

belt 48 forwardly of the pulley 46. After the finger 139 engages the strand of the belt, continued rotation of the cup-shaped member 132' will, due to the shape of the finger 139, move the belt lifter 138 about its pivot 136 (to a vertical position), and further movement of the cup-shaped member 132' will cause the belt lifter 138 to swing about the pulley 46 to the position illustrated in Fig. 10 and separate the belt 48 from driving relationship with the pulley. Reversal 10 of the procedure just described will restore the belt lifter 138 to the position illustrated in Fig. 9.

The cup-shaped member 132' includes a valve member 150 which is adapted to close that part of the slot 132 not occupied by the strands of the belt when the parts of the converter are arranged as illustrated in Fig. 10. The valve 150 will travel in a counterclockwise direction (Fig. 9) along with the belt lifter 138 and the edge of the valve 150 is so shaped as to close that part of the slot 132 not occupied by the strands of the belt so that the passageway 40 is shut off from the intake 26 of the fan.

As the cable 142 extends through the lower part of the air conducting portion of the converter 122, it is desirable to have a partition 152 arranged in the converter 122 so as to cover that part of the passageway therein through which cable 142 extends. The partition may consist of a horizontally extending plate which extends across the inside of the converter just above the cable 142 and cup-shaped member 132'. Partition 152 is provided with a circular opening in which the cup-shaped member 132' is rotatable.

A detent 154 carried by the converter 122 and adapted to engage the flanged end of the discharge 28 may be provided to indicate the inserted position of the converter. The belt 48 acting on the belt lifter 138 will effectively hold the converter in seated position within the cleaner. The detent 154 may be formed by a spring, the other end 156 of which is adapted to seat against a shoulder 158 so as to limit the penetration of the converter 122 into the converter port.

When the parts of the converter are restored to the position illustrated in Fig. 9, the converter may be readily separated from the cleaner, after which the valve 120 will automatically close the converter port.

As the cleaner is supported by its wheels when the converter is connected thereto, the cleaner may be pulled about rearwardly by the hose which is connected to the converter when the same is connected to the cleaner.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. In combination with a suction cleaner having a vertically arranged motor including a vertical shaft member and suction creating means driven thereby provided with an air inlet on the under side thereof through which said shaft members extends, a floor nozzle connected with said air inlet, a surface cleaning member associated with said nozzle, a horizontally extending belt in said nozzle between said members for driving said cleaning member, said nozzle being provided with a converter port arranged below

said suction creating means in a plane normal to said air inlet and laterally of said shaft; a converter attachment adapted to be fitted in said port and connected with and disconnected from said cleaner, one of the walls of said converter being formed to provide an opening therethrough, said converter being constructed and arranged so as to form at least part of a conduit for the flow of air from a suction cleaning tool to said port, and through which conduit and said opening formed in the wall of said converter, at least a part of said belt extends when said converter attachment is connected with said port in air conducting relationship therewith, said attachment having means thereon engageable with a part of said belt when said attachment is connected to said port in air conducting relationship therewith, for lifting said belt out of driving relationship with said shaft member, the inserted end of said converter attachment being relatively flat in cross section and said belt lifting means being mounted on said attachment for movement in a horizontal plane for cooperation with said horizontally extending belt.

2. In combination with a suction cleaner having a vertically arranged motor including a vertical shaft member and suction creating means driven thereby, a floor nozzle having a surface cleaning member operatively associated therewith, a horizontally extending belt drive between said members for driving said cleaning member, said suction creating means being provided on its under side with an air intake port through which said shaft member extends, a communication be-

30tween said air intake port and said floor nozzle through which said belt drive extends, said communication being provided with a converter port arranged below said suction creating means in a plane normal to said air intake port and laterally of said shaft; a converter attachment adapted to be connected with and disconnected from said converter port and cleaner, one of the walls of said converter being formed to provide a belt opening therethrough, said converter being

35constructed and arranged so as to form at least part of a conduit for the flow of air from a suction cleaning tool to said air intake port and through which conduit and said belt opening at least a part of said belt extends when said

40converter attachment is connected with said air intake port in air conducting relationship therewith, said attachment having means thereon engageable with a part of said belt when said attachment is connected to said air intake port in a

45communication being provided with a converter port arranged below said suction creating means in a plane normal to said air intake port and laterally of said shaft; a converter attachment adapted to be connected with and disconnected from said converter port and cleaner, one of the walls of said converter being formed to provide a belt opening therethrough, said converter being

50constructed and arranged so as to form at least part of a conduit for the flow of air from a suction cleaning tool to said air intake port and through which conduit and said belt opening at least a part of said belt extends when said

55converter attachment is connected with said air intake port in air conducting relationship therewith, said attachment having means thereon engageable with a part of said belt when said attachment is connected to said air intake port in a

60communication being provided with a converter port arranged below said suction creating means in a plane normal to said air intake port and laterally of said shaft; a converter attachment adapted to be connected with and disconnected from said converter port and cleaner, one of the walls of said converter being formed to provide a belt opening therethrough, said converter being

65constructed and arranged so as to form at least part of a conduit for the flow of air from a suction cleaning tool to said air intake port and through which conduit and said belt opening at least a part of said belt extends when said

70converter attachment is connected with said air intake port in air conducting relationship therewith, said attachment having means thereon engageable with a part of said belt when said attachment is connected to said air intake port in a

75communication being provided with a converter port arranged below said suction creating means in a plane normal to said air intake port and laterally of said shaft; a converter attachment adapted to be connected with and disconnected from said converter port and cleaner, one of the walls of said converter being formed to provide a belt opening therethrough, said converter being

76constructed and arranged so as to form at least part of a conduit for the flow of air from a suction cleaning tool to said air intake port and through which conduit and said belt opening at least a part of said belt extends when said

77converter attachment is connected with said air intake port in air conducting relationship therewith, said attachment having means thereon engageable with a part of said belt when said attachment is connected to said air intake port in a

take, a shaft driven by said motor and extending through said air intake into said communication, a surface cleaning member associated with said nozzle and a horizontally extending belt forming at least part of a driving connection which is arranged in said communication and which extends between said shaft and said member, said nozzle being provided with a converter port in a plane normal to said air intake and laterally thereof; said converter attachment comprising a hollow air conducting member having a flat end adapted to be fitted in said converter port in air conducting relationship with said fan air intake and for closing said communication between said nozzle and said suction creating means, the inserted end of said air conducting member being adapted to straddle said driving connection when said member is connected to said port in air conducting relationship therewith, said air conducting member having a part of the walls thereof cut away for receiving said driving connection so as to permit said air conducting member to be connected to said port with said driving connection extending through one of the walls of said air conducting member, a member carried by said attachment and movable to a position to close that portion of the cutaway part of said walls of said air conducting member not occupied by said driving connection, and a belt lifter carried by said attachment, said belt lifter being mounted for movement in a horizontal plane for engagement with said belt for lifting the same out of driving relationship with said shaft.

4. In a suction cleaner having a motor provided with a vertically arranged shaft, a suction creating means driven thereby and provided with an air intake formed in a horizontally extending wall thereof, a floor nozzle having an agitator operably associated therewith, an air conducting communication between said nozzle and said air intake, said shaft extending through said air intake into said communication, a horizontally extending belt between said shaft and said agitator for driving the latter during operation of said motor, said communication being provided with a converter port formed in a vertically extending wall thereof, a converter attachment comprising a hollow air conducting member having a relatively flat end adapted to be inserted and fitted into said communication through said converter port and to have its inserted end arranged in air conducting relationship with said air intake, the inserted end of said air conducting member being formed so as to accommodate said belt when said member is inserted in said communication, said air conducting member having a belt lifter carried by the inserted end thereof and arranged for movement in a horizontal plane for cooperation with said horizontally extending belt, said belt lifter being engageable with said belt and operable for disengaging the same from said shaft when said air conducting member is inserted in said communication, and means carried by the inserted end of said air conducting member and operable for closing off that part of said communication not occupied by said belt when said inserted end of said converter is arranged in air conducting relationship with said air intake.

5. In a suction cleaner having a motor provided with a vertically arranged shaft, a suction creating means driven thereby and provided with an air intake port formed in a horizontally extending wall thereof, a floor nozzle having an agitator operably associated therewith, an air conducting

communication between said nozzle and said port, said shaft extending through said port into said communication, a belt drive between said shaft and said agitator for driving the latter during operation of said motor, said communication being provided with a converter port formed in a vertically extending wall thereof, a converter attachment comprising a hollow air conducting member adapted to be inserted into said communication through said converter port and to have its inserted end arranged in air conducting relationship with said air intake port, the inserted end of said air conducting member being formed so as to accommodate said belt when said member is inserted in said communication, said air conducting member having a belt lifter carried by the inserted end thereof, said belt lifter being engageable with said belt and operable for disengaging the same from said shaft when said air conducting member is inserted in said communication, a valve carried by the inserted end of said air conducting member and operable for closing off that part of said communication not occupied by said belt when said inserted end of said converter is arranged in air conducting relationship with said air intake port, and manually operable means carried by said converter for operating said belt lifter and valve.

6. In a suction cleaner having a motor provided with a vertically arranged shaft, a suction creating means driven thereby and provided with an air intake port formed in a horizontally extending wall thereof, a floor nozzle having an agitator operably associated therewith, an air conducting communication between said nozzle and said port, said shaft extending through said port into said communication, a belt drive between said shaft and said agitator for driving the latter during operation of said motor, said communication being provided with a converter port formed in a vertically extending wall thereof, a converter attachment comprising a hollow air conducting member adapted to be inserted into said communication through said converter port and to have its inserted end arranged in air conducting relationship with said air intake port, the inserted end of said air conducting member being formed so as to accommodate said belt and shaft when said member is inserted in said communication, said air conducting member having a belt lifter carried by the inserted end thereof, said belt lifter being engageable with said belt and operable for disengaging the same from said shaft when said air conducting member is inserted in said communication, a valve carried by the inserted end of said air conducting member and operable for closing off that part of said communication not occupied by said belt when said inserted end of said converter is arranged in air conducting relationship with said air intake port, said cleaner and attachment having cooperating means for operating said belt lifter and valve by the insertion of said attachment into said communication.

7. In a suction cleaner having a motor provided with a vertically arranged shaft, a suction creating means driven thereby and provided with an air intake port formed in a horizontally extending wall thereof, a floor nozzle having an agitator operably associated therewith, an air conducting communication between said nozzle and said port, said shaft extending through said port into said communication, a horizontally extending belt between said shaft and said agitator for driving said agitator during operation of said motor, said

communication being provided with a converter port arranged in a plane normal to said air intake port, a converter attachment comprising a hollow air conducting member adapted to be inserted into said communication through said converter port and to have its inserted end arranged in air conducting relationship with said air intake port, the inserted end of said air conducting member being formed so as to straddle said belt when said member is inserted in said communication, said air conducting member having a belt lifter carried by the inserted end thereof and arranged for movement for cooperating with said horizontally extending belt for disengaging the same from said shaft when said air conducting member is inserted in said communication, and a valve carried by the inserted end of said air conducting member and operable for closing off that part of said communication not occupied by said belt when said inserted end of said converter is arranged in air conducting relationship with said air intake port.

8. In a suction cleaner having a motor provided with a vertically arranged shaft, a suction creating means driven thereby and provided with an air intake port formed in a horizontally extending wall thereof, a floor nozzle having an agitator operably associated therewith, an air conducting communication between said nozzle and said port, said shaft extending through said port into said communication, a belt drive between said shaft and said agitator for driving said agitator during operation of said motor, said communication being provided with a converter port arranged in a plane normal to said air intake port, a converter attachment comprising a hollow air conducting member adapted to be inserted into said communication through said converter port and to have its inserted end arranged in air conducting relationship with said air intake port, the inserted end of said air conducting member being formed so as to straddle said belt when said member is inserted in said communication, said air conducting member having a belt lifter carried by the inserted end thereof, said belt lifter being engageable with said belt and operable for disengaging the same from said shaft when said air conducting member is inserted in said communication, a valve carried by the inserted end of said air conducting member and operable for closing off that part of said communication not occupied by said belt when said inserted end of said converter is arranged in air conducting relationship with said air intake port, and cooperating means on said cleaner and attachment operable by the insertion of said attachment through said converter port for automatically operating said belt lifter and valve when said attachment is inserted in said communication.

9. In a suction cleaner having a motor provided with a vertically arranged shaft, a suction creating means driven thereby and provided with an air intake port formed in a horizontally extending wall thereof, a floor nozzle having an agitator operably associated therewith, an air conducting communication between said nozzle and said port, said shaft extending through said port into said communication, a horizontally extending belt between said shaft and said agitator for driving said agitator during operation of said motor, said communication being provided with a converter port arranged in a plane normal to said air intake port, a converter attachment comprising a hollow air conducting member adapted to be inserted into said communication through said

converter port and to have its inserted end arranged in air conducting relationship with said air intake port, the inserted end of said air conducting member being formed so as to accommodate said belt and shaft when said member is inserted in said communication, said air conducting member having a belt lifter carried by the inserted end thereof and arranged for movement in a horizontal plane for cooperating with said horizontally extending belt, said belt lifter during insertion of said attachment into said communication being movable in a path so as to clear the strand of the belt on one side of said shaft and so as to be engageable with the strand of said belt on the other side of said shaft and being operable for disengaging the same from said shaft when said air conducting member is inserted in said communication, and a valve carried by the inserted end of said air conducting member and operable for closing off that part of said communication not occupied by said belt when said inserted end of said converter is arranged in air conducting relationship with said air intake port, said belt lifter functioning to stretch said belt when disengaging the same from said shaft, the tension of said belt on said belt lifter functioning to hold said converter attachment in operative position in said communication.

10. In a suction cleaner, a cleaner body having a nozzle, suction creating means, a suction air passageway therebetween, a port in said body opening into said suction air passageway for receiving a converter element, an agitator movably mounted in said nozzle, power transmitting means in said air passageway for moving said agitator, a converter element insertable through said port into said air passageway between said nozzle and said suction creating means, a slot in said converter spanning said power transmitting means, and valve means on said converter for closing said slot in said converter and enclosing said power transmitting means when said converter is in position in said passageway, said valve means including means engageable with the cleaner body and operative in response to such engagement to move said valve means to slot closing position during said insertion of said converter into said suction air passageway to thereby seal said nozzle from said suction creating means, said converter having means thereon engageable with a part of said power transmitting means for breaking the drive to said agitator when said converter is in position in said air passageway.

11. In a suction cleaner, a cleaner body having a nozzle, suction creating means, a suction air passageway therebetween, a port in said body opening into said suction air passageway for receiving a converter element, an agitator movably mounted in said nozzle, power transmitting means in said air passageway for moving said agitator, a converter element insertable through said port into said air passageway between said nozzle and said suction creating means, a slot in said converter spanning said power transmitting means, valve means on said converter for closing said slot in said converter and enclosing said power transmitting means when said converter is in position in said passageway, said valve means including means engageable with the cleaner body and operative in response to such engagement to move said valve means to slot closing position during said insertion of said converter into said suction air passageway to thereby seal

13

said nozzle from said suction creating means, said converter having power transmitting disengaging means engageable with a part of said power transmitting means and with said body and operative in response to such engagement to break the drive to said agitator during said insertion of said converter into said suction air passageway.

12. In a suction cleaner, a nozzle, a fan chamber having a fan eye, a suction air passageway between said nozzle and fan eye, suction creating means in said fan chamber, an agitator movably mounted in said nozzle, power transmitting means in said air passageway for moving said agitator, a port in said passageway adjacent said fan eye for receiving a converter element into said air passageway in register with said fan eye, a converter element insertable through said port into said air passageway in register with said fan eye, a slot in said converter spanning said power transmitting means, and valve means movably mounted on said converter for movement to closed and opened positions with respect to said slot in said converter, said valve means when said converter is in register with said fan eye in said air passageway being in said closed position with respect to said slot and enclosing said power transmitting means to thereby seal said nozzle from said suction creating means, said valve means including means engageable with a part of the cleaner and operative in response to such engagement during said insertion of said converter into said suction air passageway into register with said fan eye to move said valve means to its closed position with respect to said slot, said converter being provided with means thereon engageable with a part of said power transmitting means for breaking the drive to said agitator when said converter is in position in said air passageway.

13. A device according to claim 3 in which said member and said belt lifter are provided with actuating means, engageable with a part of the cleaner and operative in response to such engagement during insertion of said converter into said communication to move said member to its closed position and said belt lifter to lift said belt out of driving relationship with said shaft.

14. A device according to claim 4 in which said valve is provided with actuating means, engageable with a part of the cleaner and operative in response to such engagement during insertion of said converter into said communication to move said valve member to its position for closing off that part of the communication not occupied by the belt.

15. A suction cleaner including a body having a floor nozzle, a motor, a suction fan driven by said motor and having an air inlet, an air passageway extending between said nozzle and said fan air inlet, a surface cleaning agitator associated with said nozzle and operable for acting upon a surface covering presented to said nozzle during cleaner operation, belt driving means driven by said motor, a belt in said passageway and forming at least part of a driving connection between said agitator and said belt driving means for driving said agitator during operation of said fan, said air passageway being provided with a converter port and a closure therefor, a converter comprising a hollow air conducting member insertable in said passageway through said port and arranged to obstruct said passageway so as to prevent the flow of air from said nozzle to said fan air inlet, and said converter

14

when arranged in said converter port being in air flow relation with said fan air inlet, a portion of said belt being disposed in the path of movement of a part of said converter during the insertion thereof, said part of said converter, during insertion thereof into said passageway, being engageable with said portion of said belt and actuated by the inserting movement of said converter for shifting the belt out of driven relation with said belt driving means so as to break the driving relation between said motor and said agitator, said converter being formed to accommodate said belt when said converter is so arranged in said passageway.

16. A suction cleaner according to claim 15 wherein withdrawal of said converter from said converter port automatically reestablishes the driving relation between said belt and said belt driving means.

17. A suction cleaner including a body having a floor nozzle, a motor, a suction fan driven by said motor and having an air inlet, an air passageway extending between said nozzle and said fan air inlet, a surface cleaning agitator associated with said nozzle and operable for acting upon a surface covering presented to said nozzle during cleaner operation, belt driving means driven by said motor, a belt extending through said passageway and arranged in driving relation with said agitator and said belt driving means for driving said agitator during operation of said fan, said air passageway being provided with a converter port and a closure therefor, a converter comprising a hollow air conducting member insertable in said passageway through said port, the inserted end of said converter being shaped to fit and seat in said passageway so as to prevent the flow of air from said nozzle to said fan air inlet, and said converter when so arranged in said converter port being in air flow relation with said fan air inlet, means for securing said converter when so arranged to said cleaner, a portion of said belt being disposed in the path of movement of a part of said converter during the insertion thereof, said part of said converter during movement of said converter toward its seat in said passageway being engageable with said portion of said belt and operable by the inserting movement of said converter for shifting said belt out of driven relation with said belt driving means so as to break the driving relation between said motor and said agitator.

18. A suction cleaner including a body having a floor nozzle, a motor, a suction fan driven by said motor and having an air inlet, an air passageway extending between said nozzle and said fan air inlet, a surface cleaning agitator associated with said nozzle and operable for acting upon a surface covering presented to said nozzle during cleaner operation, belt driving means driven by said motor, a belt extending through said passageway and arranged in driving relation with said agitator and said belt driving means for driving said agitator during operation of said fan, said air passageway being provided with a converter port, converter means adapted to be inserted in and positioned across said passageway and shaped to fit in said passageway so as to prevent the flow of air from said nozzle to said fan air inlet and to establish flow of air into said passageway through said converter port during operation of said fan, a portion of said belt being disposed in the path of movement of a part of said converter during the

insertion thereof, said part of said converter means during such inserting movement of said converter means toward such position across said passageway being engageable with said portion of said belt and operable by the inserting movement of said converter for shifting said belt out of driven relation with said belt driving means so as to break the driving relation between said motor and said agitator, and said converter means being formed to accommodate said belt when so positioned.

19. In a suction cleaner, a nozzle, a fan chamber having a fan eye, a suction air passageway between said nozzle and fan eye, suction creating means in said fan chamber, an agitator movably mounted in said nozzle, power transmitting means in said air passageway for moving said agitator, a port in said passageway adjacent said fan eye for receiving a converter element into said air passageway in register with said fan eye, a converter element insertable through said port into said air passageway in register with said fan eye, a slot in said converter spanning said power transmitting means, and valve means movably mounted on said converter for movement to closed and opened positions with respect to said slot in said converter, said valve means when said converter is in register with said fan eye in said air passageway being in said closed position with respect to said slot and enclosing said power transmitting means to thereby seal said nozzle from said suction creating means, said valve means including means engageable with a part of the cleaner and operative in response to such

5
10

engagement during said insertion of said converter into said suction air passageway into register with said fan eye to move said valve means to its closed position with respect to said slot, said converter being provided with power transmitting disengaging means engageable with a part of said power transmitting means and with said body and operative in response to such engagement to break the drive to said agitator during said insertion of said converter into said suction air passageway.
